TERMINAL CONNECTOR

Frank B. Hewel, Pittsburgh, Pa.

Application June 6, 1940, Serial No. 339,084

3 Claims. (Cl. 173—259)

My invention relates to terminal connectors and it has particular relation to connectors for automobile batteries and the like which may be readily applied and also readily removed after being in service.

It is well known that, on account of corrosion of terminal connectors or clamping devices for the posts of automobile batteries and the like, it becomes very difficult to remove such connectors or clamps for battery repairs, charging the battery, replacement of the cables, etc., and numerous devices have been proposed in the past for overcoming to a greater or less degree this undesirable condition.

It is an object of my present invention, therefore, to provide a battery connector operating on the lever principle, whereby the connector or clamp may be readily removed from the battery post by causing an enlargement of the opening for receiving the post.

Another object of my invention is to provide a movable member pivoted to the usual split ring member and having a portion adapted to close the split, such portion being movable away from the battery post through the operation of a lever principle when it is desired to remove the connector.

A further object of my invention is to provide a device of the character in question in which the operating lever extends over and fulcrums on the end of the battery post.

Other objects of my invention will become evident from the following detailed description, taken in conjunction with the accompanying drawing, wherein:

Figure 1 is a view in side elevation and Fig. 2 in top plan of a battery connector constructed in accordance with my present invention, applied to a post of an automobile storage battery, for example;

Fig. 3 is a bottom view in plan of the connector device illustrated in Figs. 1 and 2;

Fig. 4 is a view, partially in section and partially in elevation showing my connector in its partially removed position; and

Figs. 5 and 6 are detailed views of certain portions of the connector shown in the remaining figures.

Referring to the drawing, I have therein shown a portion 1 of an automobile storage battery, for example, having a boss or projection 2 for supporting a tapered post or terminal 3 of the usual lead or other soft metal type, together with my connector 4, including a split ring 5 and a cable-connecting member 6 for gripping the bare end 7 of a suitable flexible cable 8.

My connector 4 comprises a bar or lever 10 extending over or above the battery post 3, being of substantially L-shape, the lower portion of the shorter leg of bar 10 being pivoted upon a

bolt 11 having a head 12 at one end and being provided with a nut 13 at the other, as best shown in Fig. 2.

The outer end 14 of the longer leg of the bar 10 may extend outwardly to a point above the cable-connecting portion 6, or at least to a considerable distance beyond the post 3, and is provided with a curved intermediate fulcrum portion 15 which, in the closed or operative position 10 of the device, may contact, although exert but little pressure upon, the end of the battery post 3, as shown in Fig. 1.

The inner side or face 16 of the short leg of the bar 10 is curved to conform to the shape of 15 the battery post 3 and cooperates with the inner face of the split ring 5, best shown in Fig. 5, to entirely surround the battery post 3 and to make good electrical contact therewith in the operative position of the connector shown in Fig. 1.

20 For the purpose of maintaining the bolt 11 in its desired position so that it will not work loose, a lug 17 is provided on the side of the split ring 5 adjacent to one face of the bolt head 12.

The split ring 5, shown in plan view in Fig. 5, 25 is of a familiar character: in general, comprising a U-shaped member having its curved base 18 preferably integrally merged into the cable-connecting member 6 and having two oppositely-disposed outwardly-extending legs 20 and 21, so that this split ring is substantially U-shaped in plan view. Suitable openings 22 and 23 are disposed near the respective outer ends of the legs 20 and 21 for receiving the bolt 11.

It is preferable that the parts of the illustrated 30 connector 4, including the split ring 5 and cable-connecting portion 6, be made of some non-corrodible metal to prevent the battery acid, etc., from eating the metal away quickly. However, such metal is necessarily rather brittle in character,

40 and in order to suitably reinforce the split ring 5 and at the same time keep it relatively thin in cross-section, I provide a reinforcing wire 25, shown by itself in Fig. 6, which is cast in the split ring 5 and is of such contour as to be present just below the surfaces of the entire split ring 5. One end of the bent wire 26 is disposed near the curved base 25 of the split ring, as shown in Fig. 5, and extends around the curved portion up to a point near the end of the leg 20 where it is bent upon itself, as indicated by the reference character 27 in Figs. 4 and 6. The conductor 25 then extends along the other side of the leg 20 and around the other side of the curved portion 25, the outermost point being indicated at 28 in Figs. 4 and 6, the wire 25 then continuing around the curved portion and along the rear side of the leg 21 to the outermost point indicated by the reference character 29. The wire 25 is then again reversed on itself, passing along the front side of the leg 21 and around

50 the reference character 27 in Figs. 4 and 6. The conductor 25 then extends along the other side of the leg 20 and around the other side of the curved portion 25, the outermost point being indicated at 28 in Figs. 4 and 6, the wire 25 then continuing around the curved portion and along the rear side of the leg 21 to the outermost point indicated by the reference character 29. The wire 25 is then again reversed on itself, passing along the front side of the leg 21 and around

the front side of the curved portion 25 to the end 30 of the wire 25 close to the beginning point 26 of the wire. However, if desired, a continuous or one-piece reinforcing wire may be employed instead of the illustrated double-ended wire.

In this way, a suitable and readily manufactured reinforcement is provided for the split ring 5.

It will be appreciated that the cable-connecting member 6, in lieu of occupying the position shown, may be disposed at substantially right angles thereto, that is, the cable may be attached cross-wise or lengthwise, as desired. Both types of cable-connecting members associated with split rings are available in the art, depending upon the particular service to which the device is to be applied.

The operation of my device may be set forth as follows: Initially, the bar 10, to which the split ring 5 is pivotally attached by means of the bolt 11, is moved sufficiently close to the split ring 5 to cause the inner curved face 16 of the bar 10 to extend beyond its normal operative position to a position such as shown in Figs. 3 and 4.

Consequently, the connector 4 may be readily slipped over the battery post 3, and the parts may then be driven into their final position by applying a hammer to the left-hand portion of the longer leg of the bar 10, that is, to the upper left-hand corner portion of Fig. 1. This action drives the parts into the position shown in Fig. 1 where the above-mentioned inner curved face 16 makes close contact with the adjacent portion of the battery post 3 so that the post is entirely enclosed by a combination of this curved face 16 and the inner face of the curved portion 19 of the split ring. The fulcrum portion 15 of the bar 10 makes contact with but exerts little pressure upon the end of the battery post 3 in this operative position of my connector, as shown in Fig. 1.

The nut 13 may then be tightened to the desired degree on the bolt 11, to insure holding the clamp on the post free from vibration, etc. However, it will be noted that whereas in prior art split rings, the ends could be damaged by being forced inwardly over the tightening bolt, such damage cannot occur with the present invention, as the short end of the lever 10 is disposed on the bolt 11 between the ends of the split ring 5.

In this way, a battery connector making a satisfactory electrical and mechanical connection with the battery post 3 is provided, it being readily applied by means of a hammer or other implement applied as noted above.

When it is desired to remove the connector for any purpose, it is merely necessary to first loosen nut 13 and then apply a hammer to the overhanging end 14 of the lever or bar 10, whereby the fulcrum portion 15 acts upon the end of the battery post 3 to effect the following results:

In accordance with the well known lever principle, the application of a force at the end 14 of the lever to force it downwardly around an intermediate fulcrum, such as 15, causes the load portion of the lever, including the portion surrounding the bolt 11 and also the split ring 5, to be moved upwardly, and at the same time the curved face 16 of the bar 10 is moved outwardly away from the surface of the battery post, as illustrated in Fig. 4.

As a result, a few hammer blows thus quickly, because of the double action mentioned, cause enlargement of the opening around the battery post 3 from the standpoint of both swinging outwardly 5 the curved face 16 of the bar 10 and moving upwardly the curved inner face of the curved portion 19 of the split ring 5. It will be appreciated that, when the connector occupies the position illustrated in Fig. 4, it may be readily removed, since any seal between the parts and the battery post 3 by reason of corrosion, etc. will have been completely broken.

From the foregoing description, it will be seen that I have provided a simple, rugged and inexpensive battery connector which may be readily applied and removed by means of a simple tool, such as a hammer, regardless of any corrosion that may have occurred around the battery post tending to seal the terminal thereto.

I do not wish to be restricted to the specific structural details or arrangement of parts herein set forth, as various modifications thereof may be effected without departing from the spirit and scope of my invention. I desire, therefore, that only such limitations shall be imposed thereon as are indicated in the appended claims.

I claim as my invention:

1. A terminal connector comprising a split ring member adapted to receive a terminal post, and 30 a disconnecting member pivoted to said ring member and having a portion substantially closing the split therein, said disconnecting member extending over the end of said post and having an intermediate fulcrum point bearing thereon 35 and an overhanging end cooperating therewith when said overhanging end is struck toward the base of the post to move said split-closing portion away from said post to permit ready removal of the entire connector therefrom.

2. A terminal connector comprising a split ring member adapted to receive a terminal post, and means comprising a lever member movably secured to said ring member at one side of said post and having an intermediate point fulcrumable on the end of said post, said lever member having a portion substantially closing the split in said ring member and having a point at the other side of said post for applying force toward the base of the post to cause a movement of said ring member and said split-closing portion on said post when said lever member fulcrums on the end of the post.

3. A terminal connector comprising a split ring member adapted to receive a terminal post, and 55 means comprising a lever member movably secured to said ring member at one side of said post, said lever member having a portion extending normally generally parallel to said split ring and being provided with a laterally extending fulcrum portion intermediate the ends thereof in 60 position to engage said terminal post to permit the lever member to fulcrum thereon, said lever member also having a portion substantially closing the split in said ring member and having a point at the other side of said post for applying force toward the base of the post to cause a movement of said ring member and said split-closing portion on said post when said lever member fulcrums on the end of the post.
